UNITED STATES PATENT OFFICE.

NOAH SHAW, OF EAU CLAIRE, WISCONSIN, ASSIGNOR TO ADDIE M. SHAW,
OF SAME PLACE.

MACHINE FOR APPLYING BABBITT-METAL LININGS TO BEARING-BOXES.

SPECIFICATION forming part of Letters Patent No. 314,614, dated March 31, 1885.

Application filed October 17, 1884. (No model.)

To all whom it may concern:

Be it known that I, NOAH SHAW, a citizen of the United States, residing at Eau Claire, in the county of Eau Claire and State of Wisconsin, have invented a new and Improved 5 Machine for Applying Babbitt-Metal Linings to Bearing-Boxes, of which the following is a specification.

My improved machine for applying the linings, which will be hereinafter described and specifically claimed, consists of different combinations of mechanical parts, whereby different series of different-sized bearing-boxes can be produced very accurately and expeditiously 15 without danger from flaws, loss from waste of metal, and with less labor and expense than heretofore, and the said combinations of parts being such that the halves of pillow-block or pedestal or other forms of divided bearing-boxes can be readily put in concentric position and clamped around any desired sized core, with their Babbitt-metal space divided 20 into two chambers; that interchangeable cores can be used, and these cores centered and adjusted for properly receiving the melted 25 Babbitt metal which forms the half-linings of the two halves of the box; and that the finished halves of the box can be quickly removed; and to effect these objects it is only 30 necessary to adjust a core-centering carriage-plate in proper relation to a determined number of a scale; place a numbered core upon a centering device of this carriage, apply the lower half of a bearing-box against a vertical 35 gage and clamp-plate of a table behind the core and upon a packed flange of the core; place the upper half of the bearing-box against the said lower half and upon the said packed flange and forward of a clamping-screw; place 40 proper-sized centering and dividing or parting plates in the rabbets of the joint between the two halves of the bearing-box, thereby laterally centering the bearing-box and dividing its Babbitt-metal chamber into two parts; 45 clamp the two parts of the bearing-box together and against the gage and clamp-plate of the table; introduce the melted Babbitt metal at one end of the bearing-box, and pour it into the spaces between the core and the 50 semi-cylindrical, or nearly so, surfaces of halves of the box; allow the metal to become solid;

unclamp and remove the upper half of the babbitted bearing-box; run back the core-carriage and remove the lower half of the babbitted box from the core; continue this operation until a full complement of a given sized babbitted bearing-box is completed; remove the core, and substitute either a smaller or larger core for a different size or series of babbitted bearing-boxes, and repeat the operation just described until a full complement of this series and size is completed.

In the accompanying drawings, Figure 1 is a perspective view of the babbetting-machine, showing also an ordinary divided bearing-box 65 put in position and ready for being filled with Babbitt metal. Fig. 2 is a top view of the same, and Fig. 3 is a vertical transverse section of the same.

The platform of the machine is designated 70 in the drawings by A, and it may consist of an ordinary table, around the edge of the top a of which a raised rim, a', may be provided in order to retain any casually-spilt Babbitt metal. On the top a, at the front side, an oblong rectangular extension is provided, and at the sides of said extension and across the table rabbeted or dovetailed guides a² are formed or applied, and on said extension and the top a, between the rabbeted guides a², a carriage-plate, B, is snugly fitted, so as to slide back and forward thereon without lateral movement. This carriage-plate is moved by means of a screw, C, which is provided with a hand-wheel, c, secured in an ordinary manner to 75 a lug, b, of the carriage, and fitted into a nut-lug, a³, of the top a of the table.

To the rear end of the plate B, an upright centering-pin, D, or other suitable centering contrivance, is firmly attached, so as to stand 80 opposite to and centrally between the ends of an upright gage and clamping-plate, E, which is either fastened to or forms a part of the top a of the table. The plate E and pin D should be exactly vertical and parallel with each other, because in the operation of the machine the bottom surface of the lower half, P', of a pedestal or other bearing-box to be babbitted is made to rest against said plate, while the pin D holds in position a metal gaged central 85 core, F, around which, excepting where certain centering and dividing or parting plates,

K, are applied, the melted Babbitt metal is poured after the other half, P, of the bearing-box and the centering and dividing or parting plates are properly adjusted for this operation.

In practice a sufficient number of accurately-turned or nicely-gaged exchangeable metal cores F of different sizes are provided to suit the different diameters of Babbitt linings for the bearing-boxes. The metal core F rests on a collar, d, of the pin D, and is provided with a broad collar, f, at its lower end, and with a porous or felt washer, f', resting on the collar f, as shown. In front of the pin D the carriage-plate B is provided with a sliding angular plate, G, which is placed on top of the carriage-plate, and which, by means of a central longitudinal rib, g, on its under side and a central longitudinal slot, b', in the carriage-plate, is kept firmly in central position with the pin D, while by means of a bolt, g', passing through it and the slot b' it can be moved toward or from the pin D any desired distance and fastened. The upright portion of the plate G is provided with an upright slot, g', through which the reduced portion of a vertically-adjustable nut, H, is passed. Said nut has a head, h, at one side of the plate G, and an outer screw, h', at the other side of the same, upon which outer screw a nut, h'', is fitted, and by this construction the nut can be raised or lowered in the slot g', accordingly as the bearing to be babbitted is long or short, and after the adjustment is made the head h can be drawn tight against the plate G, for the purpose of retaining the nut H at the desired elevation. Into the nut H a screw, I, is fitted, which is provided with a hand-wheel, i, at the outer end, and a clamp-disk, i', at the inner end, to which the screw is swiveled. With the aid of this screw the top half, P, of a pillow or pedestal bearing-box is clamped in proper relation to the lower half, P', of said box on the rear side of the core F and its centering pin D, as shown. The rabbeted fixed guides a² of the table are marked with suitable indicating scales, J, while the plate B is provided with a pointer or indicator line, j.

The scale-line which serves for indicating the number or size of a given bearing-box answers the position of the carriage-plate B pointed out by the line j. Thus, when the indicator-line j on the carriage-plate B and the indicating-scale line (marked 3 $\frac{1}{4}$) on one of the guides a² stand in line, the pin D will then have been adjusted to its right position for receiving a core for forming a Babbitt lining in a bearing-box adapted for receiving a shaft three and three-fourths inches in diameter, and in such case a core, F, three and three-fourths diameter, and marked "3 $\frac{1}{4}$," is placed on the pin D. Answering to different sizes of bearing-boxes to be babbitted, I provide different sizes of cores F and several different-sized pairs of centering and dividing

or parting plates K. With each core and pair of plates a full complement of a series of bearings can be babbitted. The plates are hung on hooks k inserted into the plate E beneath numbers conspicuously marked on the upper edge of said plate, as shown in Fig. 2, the numbers on the plate E corresponding, respectively, to the numbers on the scales J and cores F. The plates of a pair are exactly alike in form and size, and a pair are used in connection with each-sized core. A plate is inserted in each of the rabbeted surfaces of the lower half of the bearing at the point p between the two halves of the bearing, and these plates, being respectively of the required width, touch the core F and the corners of the rabbets, thereby centering the two halves of the box laterally with respect to the core F, and dividing the space for Babbitt metal into two semi-cylindrical, or nearly so, parts, and still maintaining a clamping relation between the two halves of the divided bearing, and insuring their being held in position centrally with the core, but out of contact with it except where the parting plates touch the core after once being clamped; and while the plates K center the bearing-box laterally, the gage and clamping-plate E, in conjunction with the clamping-screw I, secure the bearing in a central position with respect to the core, in a direction at right angles to the first-named position.

By means of the plates K the Babbitt metal for forming the lining in the lower and upper halves of the bearing-block is divided into two parts, and therefore the halves of the bearing-box with the Babbitt lining in them can be readily removed from the core when the Babbitt metal becomes solid. The hooks k and the numbers on the plate E, in conjunction with the scales J and numbers on the cores F, afford great convenience to the operator in the handling of the plates K, it only being necessary for him to look at the size of the core or the adjusted position of the same on the scale, and then to take from the hooks two plates which are opposite numbers corresponding to the number of or to the adjusted position of the core with respect to the number on the scale.

When the machine is to be used, the desired size of the bearing is ascertained, and a core, F, corresponding thereto is fitted on the centering pin D. The carriage-plate B is then moved by the screw C until its indicator-line j stands in line with a number of the scale on one or the other of the guides a², corresponding with the number of the bearing-box. The lower half, P', of a bearing or box is now placed endwise upon the felt or other suitable packing-washer f' of the core F, with its bottom p' touching the plate E, and its semicircular top surface a proper distance from the core, and then the upper half, P, of the box is placed in like manner on the washer f' of the said core F, with its semicircular surface

a proper distance from the core, its position being between the core and the clamp-screw I; and now the proper dividing or parting plates K are placed into the rabbeted portions 5 of the joint between the two halves of the box, with their inner edges touching the core F, and then the screw is turned up until the two halves of the bearing-box are firmly clamped against the dividing-plates and the gage and 10 clamp plate E. The melted Babbitt metal is now poured at one end of the box into the two semi-cylindrical spaces around the core F, and by the felt washer it is prevented from leaking out below, and when it has become hard 15 the screws of the carriage-plate B and of the plate G are turned back, and the babbitted bearing-box released, so that the two halves thereof can be removed, being now in a finished condition. The described operation is 20 repeated until any desired number of a given size of bearing-box are babbitted or lined with Babbitt metal, and when the full complement is babbitted the core is removed and either a smaller or larger one brought into use for the 25 operation of babbetting a series of a different-sized bearing-box.

With my invention a given number of bearing-boxes can be babbitted in a more perfect manner and in a much shorter time than is 30 possible with the ordinary modes, inasmuch as with such modes the adjustments of the core are slowly made by hand, and the divided bearing-box is necessarily provided with end guards or rims, which require to be filed or 35 turned to fit the core, and between which and the core the melted Babbitt metal frequently and wastefully as well as injuriously leaks, causing uneven places and blow-holes in the Babbitt linings of the bearing-boxes; and boxes 40 lined by my machine will all be of standard size and of the same depth from center to bottom of box, thus saving a great amount of trouble in putting the boxes in position for use. This result is secured by means of the carriage- 45 plate and the scale J.

The machine will greatly reduce the cost of babbetting or fitting boxes, it having been found by experience that with the proper convenience for melting the Babbitt metal forty 50 or fifty boxes can be easily fitted in an hour; and as the boxes are securely clamped in position by simply the clamp-screw I and plate E, and no extraneous bolts or clamps being necessary, rapid work in the babbetting operation is rendered practicable. As the machine allows of the melted metal being poured in that end of the box which is uppermost when clamped in the machine, both spaces can be filled at the same time, and the metal by 55 being thus poured in forms more perfect linings than if put in in the ordinary way, and no matter how slightly fluid the Babbitt metal may be the spaces will always be filled.

In the manufacture of the machine for use I 60 propose to furnish, say, twenty-four cores—twelve for cold-rolled shafting and twelve for

turned shafting. Those for the cold-rolled shafting as well as the others will be of different or gradually-increasing diameters, and for lining boxes for turned as well as for cold- 70 rolled shafting a provision is made by making the cores of a larger size or gage than the shafts they are to be used with, so as to allow for shrinkage of the lining of the box during the cooling of the metal, and permit the shaft 75 to turn freely in a newly-babbitted box, thereby saving the expense of scraping or turning down to the proper size, and also avoiding that destructive friction experienced from the use of babbitted boxes produced by the most 80 common means—viz., by babbetting around the shaft. The result of the friction mentioned is that many of the linings are melted before the shaft has worn them to the proper size, causing delay and expense, which is avoided 85 by having the cores of the proper size.

In the machine represented by the drawings the scale is adapted for boxes of three and three-fourths inches; three-inch for turned shafting, and a three-inch for cold-rolled shafting, and also a two and five-eighths for turned shafting, and all these will fit the same pin D, which is one and one-half inch cold-rolled. 90

With the machine an additional pin for one and one-fourth inch shaft may be provided, and 95 on which is used a core for babbetting a box for a shaft one and three-fourths inch in diameter. In a word, it will be readily understood that indicating-scales and cores can be provided which are suited to the production of 100 any and all sizes of bearings, according to the requirements of different establishments.

I do not regard it absolutely essential, while it is preferable, that the pin D should extend up entirely through the core, for it might be 105 practicable to hold, center, and adjust the core on the carriage-plate B by providing a socket or hole in the carriage-plate, and having an extension on the core below its flange, and setting and securing said stem in the 110 socket; or a short centering-boss might be provided in lieu of the pin D on the plate B, and the core fitted and secured upon the same.

The washer f' may be made of any suitable soft, or ductile, or compressible, packing material; but I prefer to make it of either wool, hair, or mineral felt; and by the use of such a washer, instead of hard metal, or a clay or putty washer, a very tight packing is secured, and danger from air-traps or blow-holes avoided. The washer f' might be placed upon the top of the carriage-plate, and the flange of the core might be left off; but I prefer to have the flange formed on the core and the washer applied upon it, as described. 115 120 125

It will be evident that if, for any reason, it should be deemed desirable to construct the machine for lining only one size of bearing-box, the core might be a fixture with the carriage-plate, and such machine with fixed core, 130 it is intended, shall be embraced as my invention under this patent.

It might be practical to employ a longer table with a longer clamp-plate E, and to provide a broader core-carriage, and set a number of core-pins D for different-sized cores 5 in a line upon this carriage, and to provide a number of separate clamping-screws I, and thus adapt the machine for lining a series of different-sized bearing-boxes at one time.

The gage-plate E might be made to move to 10 or from the core, and the core kept stationary; or both the plate E and the core might be made to move toward or from each other by appropriate mechanism, and the adjustable plate G might be made a part of or be bolted 15 firmly to the movable carriage B, but for convenience is better if constructed as shown.

What I claim as my invention, and desire to secure by Letters Patent, is—

1. In a machine for applying Babbitt-metal linings to bearing-boxes, the combination of 10 the half-boxes, the core, and the spacing-strips, substantially as and for the purpose described.

2. The combination, with a babbetting-machine table or platform provided with a gage-plate, E, of a centering and adjustable carriage-plate, B, provided with a core, F, substantially as and for the purpose described. 25

3. The combination, with a babbetting-machine table or platform having a gage-plate, E, and scale J, of a centering and adjustable carriage-plate, B, provided with a removable core, F, substantially as and for the purpose described. 30

35 4. In a machine for babbetting bearings, a table, A, comprising a rear gage and clamping plate, E, a carriage-plate, B, having a centering device for receiving a core, and a clamp-screw, I, substantially as and for the purpose 40 described.

5. A core, F, provided with a porous or other suitable packing-washer, f', in combination with an adjusting centering carriage-plate, B, and a platform or table, A, substantially as and for the purpose described. 45

6. The combination, with a babbetting-machine table or platform having a clamping-plate, E, and a centering-carriage, B, provided with a removable core, F, of a horizontally-adjustable plate, G, provided with a 50 clamp-screw, I, and applied on carriage-plate B, substantially as described.

7. The combination, with the babbetting-machine table or platform having the clamping-plate E, and core-centering carriage B, 55 carrying a removable core, F, of the horizontally-adjustable plate G, having a vertically-adjustable clamp-screw, I, substantially as and for the purpose described.

8. A babbetting-machine provided with laterally centering and dividing or parting plates K, a removable and horizontally-adjustable core, F, clamping-plate E, and a clamp-screw, I, substantially as described. 60

9. The indicating-scales J on a table or 65 platform, A, having a gage-plate, E, with a horizontally-adjustable plate, B, having an indicator, j, and centering and carrying a removable core, F, substantially as described.

10. The indicating-scale on the plate E, in combination with the hooks k, applied on said plate, the plates K, the scales J of the table A, the indicator j of carriage B, and a series of removable cores, substantially as and for 70 the purpose described.

NOAH SHAW.
